THREAD FORMING MECHANISM

Frederic Nell, Waynesboro, Pa., assignor to Landis Machine Company, Waynesboro, Pa., a corporation of Pennsylvania

Original application June 16, 1936, Serial No. 85,563. Divided and this application December 28, 1936, Serial No. 117,947

12 Claims.

(Cl. 10—145)

This invention relates to thread-forming mechanisms and more particularly to improvements in the head and chaser controlling elements of collapsible taps of the general type disclosed in United States Letters Patent to Newman No. 1,811,802.

The present application is a division of my co-pending application Serial No. 85,563, filed June 16, 1936, which application is a continuation in part of my copending application Serial No. 5,129 filed February 5, 1935.

Throughout this specification the term "chaser" is used in its broad as well as its limited sense. That is, it may mean the actual cutting tool and its carrier or holder, or the definition may be confined to the cutting element alone.

It is a primary object of the present invention to devise a thread-cutting machine having a series of slidable chasers detachably connected with a cam element, in association with means for accurately positioning all of the chasers simultaneously so that during assembly, in a single movement of the cam element, it will readily and assuredly pick up all of the chasers for interconnection therewith. More specifically, the present invention contemplates carrying out the preceding object where the cam element is centrally disposed and designed, upon axial movement, to positively move the chasers radially in both directions.

It is another major object of this invention to provide new and improved means for adjusting a chaser-controlling cam element relative to its operating means. In this connection it is an object to provide an adjustment feature which permits the removal of the chasers for sharpening without in any way dismantling the machine proper.

It is a further object of this invention to provide an improved means for firmly mounting and guiding the chaser controlling element for axial movement in the head whereby strain on the cam portions thereof is eliminated and binding and sticking of the same is hence obviated.

It is another important object of the present invention to devise a thread-cutting machine having a set of removable chasers which may be replaced accurately without disturbing the original setting of the machine and therefore without requiring trial cuts to place the machine in condition to cut the same size threads.

It is a further object of my invention to devise a thread-cutting machine comprising a main body and a detachable head designed to carry chasers, with a chaser-positioning cam that is

fully retractible to permit very quick chaser removal and immediate substitution of heads of different sizes.

The foregoing and further objects of the present invention will clearly appear upon a consideration of the following detailed description when taken in conjunction with the accompanying drawings wherein:

Figure 1 represents a fragmentary longitudinal section taken vertically through the front portion of a collapsible tap comprising a preferred form of the present invention with the parts disposed so as to extend the chasers to thread-cutting position, and with some of the thread chasers removed.

Figure 2 is an end view of the tap of Figure 1, showing the face of the head which carries the chasers, with three chasers removed to show the cam guiding slots in the head.

Figure 3 is a face view of a chaser comprising a cutter and the slidable holder upon which it is mounted, the cutter being shown in the form that it takes after being sharpened a number of times.

Figure 4 is a sectional view similar to Figure 1 but showing the parts in the position that they assume when the chasers are collapsed.

Figure 5 is a section corresponding to Figures 1 and 4 but with the chaser-controlling cam so adjusted as to be completely retracted to permit ready removal of the chasers.

The improvements and additions illustrated in the drawings and about to be described are disclosed in association with collapsible taps of the type shown in Newman Patent No. 1,811,802 and my copending application Serial No. 5,129, aforementioned; and although these are desirable forms it will be appreciated that my improvements and additions may be used on many other thread forming machines within the knowledge of those skilled in the art and within the scope of the appended claims.

With further reference to the drawings wherein like numerals are employed to designate like parts and with particular reference for the moment to Figures 1 and 2, the foundation or the main body structure of the preferred embodiment of this invention comprises an elongated hollow body 15, of which a portion only is shown, and to which is secured a chaser carrying head 16 by means of detachable studs 17. At one end the head 16 carries a plurality of cutting elements in the form of circular chasers 19 secured to radially slidable chaser holders 20. The holders 20 are insertible through, and radially slidable within, a corre-

sponding series of T-slots 22 in the front face of head 16, and at their inner ends are provided with fingers 23 which form with the bodies of the holders a series of cam slots 23a. The holders 20 are cut away at 52 for a purpose to be later explained.

The head 16 is hollow and shaped internally to slidably but non-rotatably receive a tapered chaser-controlling cam member 24, which has on its periphery a set of inclined integral fingers or wings 26 that cooperate with inclined faces on a series of ribs 36 on the cam body to provide a series of cam grooves 25. The fingers 23 of the chaser holders are snugly received within the grooves 25 of the cam member, and the wings 26 of the cam member are loosely received in the cam grooves 23a of the chaser holders. Therefore, as the cam member is moved forwardly or to the left in Figure 1, the chaser holders will be positively cammed radially outwardly; and vice versa, as the cam member is moved rearwardly, the chaser holders will be positively drawn radially inwardly.

The fingers or wings 26 are formed as integral extensions of the series of radially extending ribs or projections 36 formed on the front end of the cam element 24. The adjacent sides of these ribs meet to produce a series of V-grooves 37 on said cam element. The head 16 is provided with a circular series of radially and outwardly extending grooves 30 the adjacent sides of which meet to form a series of wedge shaped ribs or projections 42, slightly flattened at their inner ends, and terminating in an axially extending bore 34 in the head 16. Adjacent the rear of these grooves 30 the bore 34 is cylindrical as at 44 and of the same diameter as a bore 46 formed in the body 15. When assembled the bores 44 and 46 of head 16 and body 15 are aligned (see Figs. 1, 4 and 5) for a purpose to be later explained.

Just beyond the ribs 36 the cam element 24 is formed with a cylindrical portion 48 of considerably less diameter than the ribbed portion and to the rear of this cylindrical portion is a second cylindrical portion 27 of a diameter equal to that of bores 44 and 46.

When the cam element 24 is assembled in the head 16 and body 15 the cylindrical portion 27 is snugly received by the bores 44 and 46, see Fig. 1, while the front end of said cam element is rigidly supported both laterally and also against rotation by means of the reception of the ribs or projections 36 by the grooves 30. The grooves 30 and projections 36 are machined to provide a nice sliding fit and the outer portions 32 of grooves 30 are shaped to receive the wings 26 with clearances 38 and 40 between the tops and one of the sides thereof. It will also be observed that the depth of the groove 25 is greater than the width of finger 23 thereby forming a clearance 39 between the outer face thereof and the bottom of this groove. A similar clearance 41 is left between the face of fingers 26 and the bottom of grooves or slots 23a. These clearances are shown in an exaggerated manner in the lower portion of Figure 2 when the chasers 20 are removed but are covered by the chasers in the upper portion thereof. The clearance 40 also appears in Figures 1, 4 and 5.

In Figure 1, the bottom of the groove 37 formed by the ribs 36 and the part of the wedge-shaped projection 42 formed by the sides of grooves 30, normally hidden by the other parts, are indicated by dotted lines to clarify these features.

From the above it is seen that the cam element 24 is slidably mounted in the head 16 with two spaced points of lateral support, i. e. by engage-

ment of the portion 27 with the bores 44 and 46 and by the engagement of the ribs 36 with the sides of grooves 30. The large angle between the sides of the projections 42, formed by adjacent grooves 30, prevents wedging or binding and at the same time the interengagement of the ribs 36 and grooves 30 prevents rotative movement of the cam element with respect to the head.

As noted previously clearances are provided both at the top and on one side of the fingers or wings 26 which carry the cam grooves 25, as well as between fingers 26 and 23 and the bottoms of the slots or grooves 25 and 23a, into which they are received. Thus none of the stresses attendant upon the support of the cam element 24 are transmitted through the fingers 26 or the chasers 20 and binding or sticking of these parts under load is obviated.

The cam member 24 is internally threaded to receive the externally threaded end of a coupling rod 28. As will be seen later the cam member is axially adjustable relative to this rod and may be locked with respect thereto in any desired position of adjustment. The rearward end of the rod 28 is peripherally grooved and detachably coupled to an integral forked forward extension 29 of a plunger 130. The plunger 130 is disposed within the bore 46 of the body 15 and is designed for reciprocation therein.

As will be readily understood by those versed in the art the plunger 130 is to be reciprocated by some sort of control mechanism, not shown. As the general construction and mode of operation of such mechanisms are well known no further description is deemed necessary. However, reference is made to the Newman Patent No. 1,811,802 for an illustration and description of a typical form of cam element operating mechanism and also to my aforementioned application Serial No. 85,563, which discloses and claims improvements in such mechanisms. It should be understood, however, that the cam element control or operating mechanism forms no part of the present invention and the same may be used in conjunction with any desired form of such mechanism.

With particular reference now to Figures 1, 4 and 5, as aforesaid the chaser-controlling cam member 24 is adjustable longitudinally of the threaded rod 28. The means for effecting this adjustment and for locking the parts in adjusted position are as follows. The forward end of the rod 28 is tapped to receive an externally threaded sleeve 96 which extends slidably through the front end of the cam member 24 and which is provided with a head 97 that can be rotated by an actuating tool. The threaded portion of sleeve 96 has a transverse slot therethrough which receives a pair of diametrically opposed brake shoes 98 that are slideable radially in the slot and that may be forced outwardly into locking engagement with diametrically opposite portions of the tapped bore of rod 28 by rearward motion of a tapered stem 99 that fits between the shoes and forms an integral part of a manually adjustable screw 100. Screw 100 is threaded into the sleeve 96 and may be manually operated by inserting a tool through the hollow head 97 of the sleeve 96.

To effect an adjustment, screw 100 is loosened to unlock the brake shoes 98 and the sleeve 96 is rotated within the rod 28 to obtain the desired relative disposition of each part, after which the screw 100 is again locked to expand the brake shoes 98. For preventing rotation of the

rod 28 during this adjustment and for preventing undesired rotation of the rod at any other time relative to cam member 24, a yielding latch mechanism is provided comprising a plug 102 longitudinally slideable in the front end of the plunger 130, but locked against rotation with respect thereto by a pin 103. A spring 104 urges the plug forwardly, and complementary latching serrations 105 are provided on the plug and on the rear end of the rod 28. This latching mechanism is substantially identical with that shown in Newman Patent No. 1,912,298.

The adjustment just described accurately determines the thread diameter because it definitely locates the head 97 longitudinally of the device, and the head 97 in turn definitely locates the cam member 24, for in actual working positions as illustrated in Figures 1 and 4 the forward end of the cam member is always tightly in contact with the rear end of the head 97. This contact is obtained, not through rotation of the cam member which can only slide in the head 16, but through bodily rotating as a unit all of the screw-threaded elements which are housed within the cam member 24. Upon tightening the screw 100 to lock the brake shoes 98, the manipulation of the head 97 with the proper tool will cause the sleeve 96, the screw 100 and the rod 28 to rotate as a unit within the cam member to advance or retract the latter depending upon the direction of rotation of the head 97. This manual operation is permitted by the yielding latch mechanism 102 to 105 which, however, has sufficient resistance to rotation to prevent any inadvertent bodily rotation of the screw-threaded elements to get the cam member out of adjustment.

In Figure 5 the cam member 24 is shown sufficiently retracted, by the adjustment just described, to take the cam fingers or wings 26 out of overlapping engagement with the complementary fingers 23 of the chaser holders, thus permitting the chasers to be readily withdrawn radially for sharpening, adjustment or repair. A chaser is shown partly removed in Figure 5, and in Figure 3 there is shown a removed chaser having its cutting element resharpened. Due to the fact that removal and replacement of the chaser does not involve any alteration of the position of the head 97 longitudinally relative to the plunger 30, the chasers may be replaced and the screw-threaded elements bodily rotated to bring the cam 24 into engagement with the rear end of the head 97, thus assuredly bringing the parts exactly in the same position that they previously had prior to removal of the chasers. Hence, operation of the machine may be resumed to cut threads of exactly the same size, and this is important because it eliminates any trial and error adjustments and trial cuts with attendant loss of time and possible slight inaccuracies.

A highly important feature of this invention resides in the provision of means for facilitating a quick coupling between the cam members and the chaser holders upon insertion or replacement of the latter. As seen in Figures 1, 2, 4 and 5, the body of the cam member 24 has a plurality of flat inclined faces 50 corresponding in number to the number of chasers. The inclined faces terminate in forward extensions or ledges 106, as best seen for example in Figures 1, 4 and 5, which project forwardly a slight distance beyond the forward extremities of the cam wings 26. Therefore, when the chasers are replaced the 75 holders can be simply pressed radially inwardly

until their cam fingers 23 engage ledges 106 in which position every one of the cam fingers 23 is accurately located for reception by a corresponding groove 25 of the cam, and as the adjustment is performed to move the cam member forwardly 5 all of the chaser holders are picked up and intercoupled, simultaneously and without difficulty, to the cam member. The chaser holders 20 are cut away as at 52 to provide sufficient clearance for this amount of inward movement. This feature 10 is shown but not claimed in my copending application Serial No. 5,129, the claims of which are directed to another form of cam member adjusting and locking means of the character above set forth. 15

The head 16 is readily removable from body 15. Although the cam member 24 is firmly supported radially in the head 16, it can readily slide out of the same rearwardly. Access to the studs 17 is had by performing the adjustments above described to remove the chasers, and thereafter, upon removal of the studs 17 the head 16 can be replaced by a larger or smaller head which also fits the body 15 but which is designed for use in cutting another range of thread diameters. 25

The particular means for mounting and adjusting the cutting elements with respect to their holders forms no part of the present invention, but is fully set forth and claimed in my copending application Serial No. 23,901, filed May 28, 1935. 30

The invention may be embodied in other specific forms without departing from the spirit or essential characteristics thereof. The present embodiments are therefore to be considered in all respects as illustrative and not restrictive, the 35 scope of the invention being indicated by the appended claims rather than by the foregoing description, and all changes which come within the meaning and range of equivalency of the claims are therefore intended to be embraced therein. 40

What is claimed and desired to be secured by United States Letters Patent is:

1. In a thread cutting machine; a head having a plurality of radially extending guideways therein; a plurality of chasers slidably mounted in said guideways; an axially shiftable control member mounted in said head; a plurality of radial projections on said control member having inclined camming wings thereon; inclined surfaces on said member cooperating with said camming wings to form a plurality of inclined cam grooves; said chasers being provided with projections interlocked with said cam grooves; means for moving said control member to slide said chasers in said guideways; said movement terminating in each 45 direction with said chaser projections interlocked with said grooves; means for causing relative movement between said moving means and said control member to release said chaser projections from said grooves; said inclined surfaces being extended beyond said radial projections to support 50 said chasers with their projections aligned with said grooves when in released position. 55

2. In a thread cutting machine; a head having a plurality of radially extending guideways therein; chasers mounted for movement in said guideways and provided with inclined cam wings; an axially shiftable control member mounted in said head; a plurality of radial projections on said control member having inclined cam grooves 70 thereon receiving said chaser cam wings; inclined surfaces on said control member, aligned with surfaces of said cam grooves; means for moving said control member with respect to said chasers to slide said chasers inwardly and out- 75

wardly of said guideways without releasing said cam wings from said grooves; said means also being operable to effect further movement of said control member to position said cam wings on said inclined surfaces and out of engagement with said grooves.

3. A thread-cutting machine comprising a body and a complemental separate head for the body, a plurality of removable chasers slidably mounted on the head, fastening elements for detachably securing the head to the body, said elements being enclosed behind said chasers but accessible upon removal of the chasers, retractible control means in connection with said chasers to normally prevent their withdrawal, and means projecting externally of the head to permit ready retraction of said control means and removal of said chasers without dismantling any other parts of the machine.

20 4. In a thread cutting machine, a body adapted to receive any one of several complemental heads of different sizes; the head having substantially radial slideways for chaser holders opening towards its front face and recesses extending rearwardly from said slideways to the front end of said body; said slideways guiding said chaser holders for movement radially of said head but holding them against movement axially of said head; means insertible through said recesses and accessible through said slideways, when said chaser holders are moved radially outwardly, for securing the head to the body; and adjustment means for releasing said chasers from a controlling cam so that said chasers may be withdrawn sufficiently to expose said recesses.

5. In a thread cutting machine, a body and a complemental head for the body, a plurality of removable chasers slidably mounted on the head, securing means for detachably securing the head to the body, said securing means being enclosed behind said chasers but accessible upon removal of said chasers, control means for said chasers including a cam element normally coupled to said chasers and an operating means adjustably connected to said cam element, said adjustable means being operable to retract said cam element and uncouple said chasers thereby permitting removal thereof from said head and providing access to said securing means without dismantling any other parts of the machine.

6. In a thread-cutting machine having slidably mounted chasers, axially shiftable control means coupled to said chasers and comprising: a support, and a chaser-engaging member in adjustable screw-threaded connection with said support; a device for causing relative rotation of said member and said support, said device connected by screw threads to said support to establish an adjustable stop for limiting axial movement of said member in one direction; and means for locking said device against rotation relative to said support, said means comprising a brake shoe carried by said device and an element for pressing said brake shoe against said support.

7. In a thread-cutting machine having slidably mounted chasers, axially shiftable but non-rotatable control means coupled to said chasers and including a cam element and an operating means, a screw-threaded connection between said element and said operating means, an adjustable stop means threaded to said operating means and limiting relative adjusting movement of

said element and said operating means in one direction, and means to lock said stop means to said operating means whereby said operating means may be rotated thereby relative to said cam element, said locking means comprising friction members carried by said stop means and engaging said operating means.

8. In a thread-cutting machine, the combination set forth in claim 7 wherein said friction members are threaded to cooperate with the threaded connection between said stop means and said operating means.

9. In a thread-cutting machine, a body portion provided with a head, a cylindrical hole in said body portion, said head having an axial aperture provided with inwardly extending key members and terminating in a cylindrical recess, said hole and said recess being of the same diameter and aligned to form a continuous bore, a chaser controlling element slidably received by said bore and aperture, spaced bearing portions on said element engaging said bore and said key members respectively.

10. In a thread-cutting machine, a body portion provided with a head, a cylindrical opening in said body portion, an axial aperture in said head terminating at one end in a cylindrical recess, said opening and said recess being aligned and of the same diameter thereby forming a continuous bore, a circular series of axially extending grooves in said head opening into said aperture, a chaser controlling element slidably received by said head and said body on spaced bearing surfaces, said bearing surfaces comprising a series of radially extending projections carried by one end of said element and snugly received by said grooves, and a cylindrical portion on the other end of said element snugly received by said bore.

11. In a thread-cutting machine, an apertured head portion carrying movable chasers, a circular series of axial grooves in said head opening into said aperture, radial grooves in a face of said head overlapping said axial grooves and guiding said chasers, cam fingers on said chasers having inclined inner surfaces, a chaser controlling element provided with a series of projections having inclined outer surfaces carrying portions extending at right angles thereto and forming therewith cam grooves, said projections slidably fitting in said axial grooves to support said element independently of said extending portions, and said cam fingers being received within said cam grooves.

12. In a thread-cutting machine, an apertured head carrying radially slidable chasers, a cam element coupled to said chasers and slidably supported in said head, a circular series of grooves in said head and a matching series of radial projections on said element adapted to be snugly but slidably received in said grooves, whereby said element is rigidly supported in said head against lateral or rotational movement; cam means carried by said radial projections and extending at right angles thereto, cooperating cam engaging fingers carried by said chasers and coupled to said cam means, said grooves being provided with radial extensions of sufficient size to receive said cam means with clearances whereby stress on said cam element is transmitted to said head solely through said radial projections and binding of said cam means and said fingers is obviated.

FREDERIC NELL
